LEO M. GRAY AND MILTON H. TERPENING, OF FULTON, NEW YORK.

BALING-PRESS FOLLOWER BLOCK.

Application filed April 23, 1921. Serial No. 464,014.

To all whom it may concern:

Be it known that we, LEO M. GRAY and MILTON H. TERPENING, of Fulton, in the county of Oswego, in the State of New York, have invented new and useful Improvements in Baling-Press Follower Blocks, of which the following, taken in connection with the accompanying drawings, is a full, clear, and exact description.

10 This invention relates to a dividing block for baling presses of the power driven reciprocatory plunger type for baling hay and analogous uses, the dividing block being used and reused as the head and follower in 15 the formation and separation of the bales by successive movement of the plunger preparatory to wiring.

These dividing blocks are made to conform more or less closely to the cross sectional form and size of the chamber in which the plunger is movable, and it sometimes happens (more or less frequently) that portions of the hay or other material which is being pressed collects upon the bottom of the chamber under the lower edge of the dividing block thereby raising the latter a sufficient distance to cause its upper edge to come in contact with the upper side of the baling chamber as it is moved forward by the plunger, and owing to the high power with which the plunger is operated, frequently results in breaking the upper portion of the dividing block, and as ordinarily used necessitates replacement by an 30 entirely new dividing block or considerable delay in repairing the broken block, all of which, aside from the loss of time, add greatly to the cost of baling, and the main object of our present invention is to reduce 35 to a minimum the difficulties attending these breakages by providing means whereby when the block is broken, it may be easily and quickly repaired and reused without material loss of time, labor or expense.

Another object is to confine the breakage and incidental mutilation of the plate to a relatively small area along a well defined line of cleavage so that the repairs may be 50 standardized or made substantially uniform for all breakages without extra parts other than those used in the original plate, or when, the breakable parts are exhausted they may be readily replaced at comparatively small cost.

Another object is to provide means

whereby the block or dividing plate may rest squarely upon the bottom of the baling chamber to hold the block in an upright position and to reduce wear of the lower 60 edge thereof.

Other objects and uses relating to specific parts of the device will be brought out in the following description:

In the drawings:

Figs. 1, 2 and 3 are respectively, a top plan, a side elevation and an edge view of a dividing block or plate embodying the various features of our invention.

Fig. 4 is an enlarged vertical sectional view partly broken away taken on line 4—4, Fig. 2.

Figs. 5 and 6 are enlarged detail sectional views taken respectively, on lines 5—5 and 6—6, Fig. 2.

As illustrated, this dividing plate is made to conform closely to the cross-sectional area of the interior of the baling chamber with sufficient clearance between the edges thereof and walls of the chamber to permit it to move freely therein, said block being substantially rectangular in face view and having its front and rear faces substantially flat and parallel, both sides being identical to enable it to be used in reverse positions.

This dividing block is preferably made of wood with suitable metal reinforcements or wearing plates where needed as hereinafter more fully described and is preferably composed of lower and upper sections —1— and —2—, the lower section constituting the main body and is relatively wide vertically while the top or head section —2— is relatively narrow vertically, said sections being arranged edge to edge in substantially the same plane with their adjacent edges in a plane at substantially right angles to the upright sides of the block and normally held in slightly spaced relation to form a wire-receiving-groove —3— which also forms the plane of breakage in case the head section —2— should contact with the upper wall of the baling chamber with sufficient resistance or force to break the connecting strips, presently described, while the block is being advanced by the power driven plunger of the press.

The breakable means normally connecting the lower and upper sections —1— and —2— preferably comprises a pair of wooden strips —4— extending vertically across the meeting edges of said sections

equal distances from the outer upright edges thereof and having their upper ends normally secured in vertical openings or guide ways —5— in the upper section —2— by 5 means of screws —6—, while their remaining portions extend downwardly through registering openings —7— in the lower section —1— in which they are secured by screws —8—, the screws —6— and —8— 10 constituting means for holding the break strips —4— and sections —1— and —2— against relative vertical movement when the parts are adjusted for use as a dividing plate or block.

15 The registering openings or guide ways —5— and —7— of each set extend from bottom to top of the block as a whole and in like manner, the break strips —4— when first assembled in the block extend from the 20 bottom to the top thereof and are held in place against vertical displacement by the screws —6— and —8—, which in case of breakage at —3— may be easily and quickly removed to permit the removal of the break 25 strips —4— and the reinsertion of the longer portions of said strips from the top downwardly where they may be resecured to the sections —1— and —2— by the same screws —6— and —8—.

30 That is, assuming that the dividing block is being used in the baling press in the usual manner and is being advanced forwardly by the plunger and that through the imperfect seating of the bottom of the block, the 35 upper edge thereof should be sufficiently elevated to encounter a portion of the top of the baling chamber with sufficient resistance to break the strips —4— between the lower and upper sections —1— and —2—, thereby causing the upper section —2— to be tilted rearwardly in the direction indicated by dotted lines in Fig. 4 sufficiently to clear the under side of the top of the baling chamber, which would allow the 40 dividing block to be forced forwardly by the plunger to the ends of the strokes thereof at which time the machine could be stopped long enough to remove the broken dividing block for repairs.

45 These repairs can be made easily and quickly by simply removing the screws —6— and —8— and then driving the broken parts of the strips —4— out of their respective sockets —5— and —7—.

50 The shorter broken sections of the strips may be thrown away but the longer sections are reinserted in the sockets —5— and —7— a sufficient distance to hold the said sections in vertical alinement and thereby to restore 55 the plate or block to proper condition for further use by simply retightening the screws —6— and —8—.

It is evident that the same break strips —4— may be reused several times or after 60 several breakages as long as any portions

thereof remain of sufficient length to be engaged by both of the screws —6— and —8—, which it will be seen upon reference to Fig. 2 are relatively short distance apart as compared with the total height of the dividing 70 block.

The break strips —4— are of sufficient strength to withstand any of the ordinary baling pressures or other strains, but are usually reinforced along their front and rear sides by metal friction plates or straps —9— which extend entirely through the registering openings —5— and —7— to lie against the front and rear walls thereof and thereby to not only tie the sections —1— and —2— together but serve as guide plates along and against which the strips —4— are more readily and easily movable during their insertion and withdrawal into and from their respective openings, and yet they are sufficiently pliable to readily bend without breaking in case the upper section thereto should become deflected from its normal position in the manner previously described to such an extent as to break the strips —4—, thus permitting the friction plates to be easily and quickly restored to their normal straight positions after the broken parts of the strips have been removed, the upper ends of said plates being preferably deflected laterally or outwardly upon the upper edges of the section —2— to which they are secured by screws —10—.

55 The break strips —4— are made to fit snugly in their respective guide openings —5— and —7— and against the inner faces of the friction plates —9—, which, aside from their securement to the upper face of the upper section —2— are unattached to the lower section —1— except by frictional engagement with the adjacent walls of the guide openings —7— and contiguous faces of the break strips —4— so that in case the upper section becomes broken or tilted laterally by the breaking of the strips —4—, the portion of the friction plates —9— in the lower section —1— will be free to draw upwardly to compensate for the deflected position of the upper section —2—.

60 That is, by removing the screw —6—, the upper section —2— with the friction plate —9— and break-strips —4— may be withdrawn upwardly from the lower section —1— to facilitate the removal of the broken parts of the break-strips and replacement of the longer section or by new break-strips, thus permitting a prolonged use of the same dividing block for an indefinite period of time.

65 The lower corners of the upper section —2— are reinforced and protected against successive wear or mutilation by the breaking of the strips —4— along the line of separation —3— by means of angle irons —10—, while the upper corners of the section —1—

are similarly protected by metal bars or plates —11— which together with the bars or angle irons —10— extend across both sides of the dividing block from side to side.

5 The opposite sides of the dividing block are provided with additional wire-receiving-grooves —3'— arranged in vertically spaced relation parallel with the separating space —3— between the lower and upper sections —1— and —2— and are provided with metal bottom plates —12— extending lengthwise of and across the bases thereof to afford free passage for the wires used in binding the baled hay, said plates being secured to the inner faces of the outer layers of the block adjacent the outer faces of the friction plates —9—, thereby reinforcing the block where weakened by the grooves —3'— and also affording metal bearings for the plates —9— to reduce the wear of the latter upon the wood.

The front and rear faces of the opposite edges of the dividing block are further reinforced by wearing plates —13— of suitable metal to be engaged by the retainer dogs commonly used in baling presses for holding the compressed hay and followers or dividing plate against backward movement following each forward stroke of the plunger.

The lower edge of the dividing block is further reinforced by metal feet or bearing members —14— which extend forwardly and rearwardly across the lower edge of the block and are secured thereto between but in close proximity to the inner faces of the guide openings —7— for the break strips —4—, the lower edges or sides of the reinforcing members —14— being substantially flat for holding the dividing block in a vertical position when resting upon the bottom wall of the baling chamber.

The upper section —2— may be provided in opposite faces thereof with recesses —15— to form handles by which the dividing block may be removed and replaced from and within the baling press.

The main body of the dividing block is preferably made of opposite side and intermediate layers of wood secured together by any suitable fastening means and arranged so as to economically form the openings —5— and —7— in the lower and upper sections —1— and —2—.

55 Under normal conditions this dividing block is used and operates in the usual way, but in case of improper seating of the same upon the bottom of the baling chamber by the accumulation of hay or other foreign matter under the lower edge thereof to such an extent as to cause its upper edge to engage the mouth of the baling chamber, then the advanced movement of the plunger and dividing plate actuated thereby would cause the upper section —2— to engage the top of

the chamber with sufficient resistance to break the strips —4— along the line of separation —3—, thereby tilting the section —2— rearwardly in the direction indicated by dotted lines in Fig. 4 without materially damaging the remaining portions of the dividing plate or parts of the baling chamber, and under such conditions the screws —8— may be easily and quickly removed whereupon the top section —2— and friction plates —9— thereon may be withdrawn from the lower section —1— and the broken parts of the strips —4— driven out from between the plates —9—, the longer lower sections being then reinserted between the plates —9— after the latter have been straightened and again brought into registration with the guide openings in the lower section —1— and inserted therein, the screws —8— being then retightened to hold the strips —4— and sections —1— and —2— in operative relation ready for reuse.

What we claim is:

1. A dividing block for baling presses, said block being composed of separable sections arranged edgewise one above the other with a wire-receiving-space between the adjacent edges, and a break-strip fastened to one of the sections and extending across the wire-receiving-space and slidably engaging the other section for normally holding the other section in the same plane.

2. A dividing block for baling presses, composed of sections arranged edgewise one above the other and provided with registering guide-ways extending transversely of the adjacent edges of said sections, and a break-strip inserted in said guide-ways.

3. A dividing block for baling presses, composed of sections arranged edgewise relatively to each other and provided with registering guide-ways extending transversely of the adjacent edges of said sections, a break-strip inserted in said guide-ways, and means for normally holding the break-strip and sections against relative movement lengthwise of the break-strip.

4. A dividing block for baling presses, composed of lower and upper sections arranged edgewise relatively to each other in substantially the same vertical plane and provided with vertical guide openings registering with each other, a break-strip inserted in said guide-openings, and means for holding the break-strip against endwise movement relatively to said sections.

5. A dividing block for baling presses, composed of sections arranged edgewise one above the other in substantially the same plane and provided with separate sets of guide-openings extending transversely of the meeting edges of said sections, those of each set being registered with each other, break-strips inserted in the registering openings, and means for holding the break-

- strips against endwise movement relatively to said sections.
6. A dividing block for baling presses, composed of sections arranged edgewise relatively to each other in substantially the same plane and provided with registering openings extending transversely of their meeting edges, opposed friction plates passed through said openings in spaced relation and secured to one of said sections, a break-strip inserted in said openings between the plates, and means for holding the break-strip and sections against relative movement lengthwise of the break-strip.
15. 7. A dividing block for baling presses, composed of lower and upper sections arranged edgewise one above the other in substantially the same plane and provided with registering upright guide-ways, a break-pin inserted through said guide-ways, means for holding the break-pin and sections against relative vertical movement, and angle irons secured to and along the corners of the lower edge of the upper section to prevent mutilation of said corners in case of breakage of the pin along the adjacent edges of the sections.
8. A dividing block for baling presses having a head or top section relatively narrow vertically, break-pins secured to the top section and extending downwardly through openings in the lower section, and means for normally securing the break-pins to the lower section.
35. 9. A dividing block for baling presses, comprising wooden sections arranged edgewise one above the other and provided with metal reinforcing plates along the corners of their adjacent edges, said sections having vertically registering guide openings, a wooden break-strip inserted in said guide-openings, means for normally holding the break-strip and sections against relative vertical movement, and metal friction plates inserted through the registering-openings along opposite sides of the break-strip.
10. A dividing block for baling presses, comprising wooden sections arranged edgewise one above the other, wooden break-strips inserted through vertical openings in said sections across the adjacent edges thereof, and metal wearing pieces secured across the lower edge of the lower section out of registration with the vertical openings therein and provided with substantially flat lower faces to support the dividing block in an upright position.
11. A dividing block for baling presses having a separable top section relatively narrow vertically, and wooden break-strips passed through openings in the guide plate transversely of and across the plane of separation of the top section from the bottom section.
12. A dividing block for baling presses having its opposite sides provided with parallel wire-receiving-grooves in vertically spaced relation, and metal plates extending across the bases of some of the grooves from edge to edge of the dividing block.
13. A dividing block for baling presses, composed mainly of wood, and metal plates secured to opposite faces of the wood portions of the block near the upright edges thereof to form wearing plates for engagement by the retaining dogs of the press.
14. A dividing block for baling presses, comprising lower and upper sections arranged edgewise one above the other, the top section being relatively narrow vertically, both sections having registering sets of guide-openings therethrough from top to bottom, and wooden break-strips inserted through said openings.
15. A dividing block for baling presses composed of separable sections arranged edgewise relatively to each other and relatively movable connections between said sections.
16. A dividing block for baling presses composed of separable sections arranged edgewise relatively to each other in spaced relation one above the other, the upper section being of relatively narrower vertical height than the lower section, and connections between the adjacent edges of said sections movable relatively thereto for normally holding the sections in substantially the same vertical plane.
17. A dividing block for baling presses comprising lower and upper sections, and yielding connections between said sections.
- In witness whereof we have hereunto set our hands this 15th day of April 1921.
